WIRE EXTRACTOR

Henry L. McCarley, Compton, Calif., assignor to Northrop Aircraft, Inc., Hawthorne, Calif., a corporation of California

Application October 23, 1953, Serial No. 387,849

4 Claims. (Cl. 81—9.5)

This invention relates to tools and methods used in assembling electrical equipment, and more particularly to a small hand tool and its use in a novel method for extracting a wire from a shielded cable.

It is general practice in the installation of shielded electrical cable to attach the metallic shield to a ground contact point adjacent the terminal to which the inner wire is secured. The only practical way of doing this is to push apart the strands of the metallic shielding and withdraw the inner wire at the point desired leaving the shielding undamaged and long enough to reach the ground contact. There are various other situations in which it is necessary to bring the wire out through the shielding of the cable, but the operation has always been tedious and haphazard, usually resulting in serious damage to the shielding material, the inner wire, or both.

In brief my invention comprises a device for extracting the inner wire from the center of a shielded cable at any desired point, and includes a pointed awl-like member having a channeled shank, tapered from the point to provide progressively increasing depth within the channel and fitted with a suitable handle to which is attached the adjacent portion of the awl shank. In use the awl point is slipped through the shielding material, along the inner wire, then out through the shielding at the point where it is desired to extract the wire. Bending the forward portion of the cable widens the opening in the shielding at the point of the awl and permits the wire, sliding through the channel of the awl shank, to be withdrawn through the shielding.

This basic manipulative procedure is varied and augmented in a number of ways to suit different types of installations.

There are several important objects of this invention.

One important object of this invention is the provision of means for extracting a wire from a shielded electrical cable at any desired point in the length of the cable.

Another important object of this invention is the provision of means for the extraction of a wire from a shielded electrical cable without damage to the outer metallic shielding, or the wire.

A further object of this invention is the provision of means for the extraction of a relatively small loop of inner wire from a shielded electrical cable, for the purpose of making a connection to that wire, without interrupting the through circuit nor damaging the metallic shielding.

Other important objects of this invention will become apparent from the following description of one preferred embodiment of the invention and reference to the accompanying drawings, in which:

Figure 1 is a diagrammatic view of one embodiment of the tool of my invention showing the tapered shank of the awl, and, in cross sectional diagrams 1a, 1b and 1c, the progressive increase in depth at distances spaced from the point.

Figure 2 is a diagrammatic view of the top of the wire extractor showing the relative positioning of the clamp-

2

ing means, the open side of the awl shank and the handle member.

Figure 3 is a perspective view showing the manner in which the awl point is inserted between the metallic shielding and the inner wire of the cable.

Figure 4 is a view similar to Figure 3 showing the manner in which the awl shank channel fits around the inner wire and presses aside the strands of the shielding as it emerges from the shielding at the point where the inner wire is to be extracted.

Figure 5 is a perspective view showing the emergence of the inner wire at the point where the cable is bent back along the awl shank.

Figure 6 is a view similar to Figure 5 showing the inner wire being withdrawn from the cable through the concave awl shank channel and the second aperture in the metallic shielding adjacent the awl point.

Figures 7 to 11 inclusive, are diagrammatic views intended to illustrate possible variations in the general manipulative method illustrated in Figures 3 to 6 inclusive.

Referring again to Figure 1 which is a side view of one preferred device embodying my invention of a tool for extracting a wire from within a shielded cable, it is seen that the device includes three main components: a tapered awl-like shielding penetrating member 1, at left, terminating in a rounded flat point 2, spaced from a handle member 5, with a pivoted clamping means 6 mounted on the handle.

The shank portion of the awl member 1 is formed longitudinally in the manner of a U-shaped channel having parallel sides or walls 3 and 4 in Figure 2, tapered from the awl point to provide a progressively deeper concavity within the shank channel as indicated in cross section diagrams 1a, 1b and 1c which show the increased depth in inner area of the shank at sections spaced from the awl point 2, and thereby constituting an instrument falling within the category of a probe and being effective also as a riving hook, but probably more accurately described as a sharp pointed longitudinally extended hollow wedge. The width of the concave inner area 12 remains constant throughout the length of the shank, and the size of the awl selected for use in any particular case will be based upon its interior channel width and the diameter of the inner wire to be extracted from the cable so that the wire is slideable within the channel at the point of deepest concavity thereof. The channel form of the awl terminates in a solid butt section.

The awl member 1 is removably secured within a suitable handle member 5 which, in turn, is fitted with a clamping means in the form of a forwardly extending arm 6, pivoted to the handle member 5 on an axis perpendicular to the longitudinal axis of the handle and awl members, and terminated in a flat transverse section 7 disposed across the open side of the awl shank channel and movable into contact therewith by thumb pressure of the operator, as shown in Figure 6. Upon release of pressure on the transverse section 7, it and the arm 6 are returned to the normal non-contacting position shown in Figure 1 by a spiral spring 9 in Figure 1 located between arm 6 and handle member 5.

Engagement of the limit pin 10, extending from the arm 6, with the upper end of an arcuate slot 13 in the side of the handle member holds the transverse clamping member 7 any desired spacing from the awl shank 3. Loosening of a set screw 14 in the handle member 5 which engages with the butt section of the awl permits removal of the awl member 1 from the longitudinal slot 15 in the handle member for substitution of other sizes.

Manipulation of the device in actual use is simple:

Figures 3 to 6 illustrate the steps involved in extracting a wire with the aid of the device of my invention. The

tool is quite versatile and it can be advantageously employed in various assembly and installation situations; but the first procedure that will be described and illustrated is generally representative of its practicability in use.

Having made necessary measurements at the point of installation, the assembler finds the point along the length of the cable at which the inner wire must be removed from within the shielding. The point 2 of the awl portion 1 is worked in between the strands of the metallic shielding a short distance nearer the free end of the cable 18 than the point at which the wire is to be removed. Lateral movement of the awl point 2 serves to widen the opening in the shielding 16 making it possible to slide the awl member along the inner surface of the shielding so that the wire aligns within the concave channel of the awl shank.

When the awl point 2 has been advanced under the shielding to the desired point in the length of the cable, the awl point is worked outwardly through the woven shield as seen in Figure 4. The main cable body 19 is then bent downwardly close to the handle 5 as shown in Figure 5, thus piling up wrinkled folds of shielding material 16 on the awl shank adjacent the handle and causing a small loop of the less resilient inner wire 17 to form near the awl point 2.

This small loop is easily enlarged and the inner wire 17 withdrawn through the awl shank channel while the shielding material is restrained from slipping off the awl shank by pressure of the clamp 7 as seen in Figure 6.

In addition to the particular method for extracting a portion of inner wire just described, there are certain variations of the same general manipulative procedure better suited to other circuit and installation requirements, some of which are illustrated in Figures 7 to 11, inclusive.

One variation, for instance, wherein the awl point is inserted at the square-cut end of the cable between the inner wire and the outer shielding material, rather than through the side wall of the cable, is shown in Figure 7. The awl point 2 after being inserted at cable end 20, is pressed inwardly of the length of the cable with the folds of accumulated shielding material worked downwardly on the awl shank 21 in Figure 8, then cable body 24 is drawn back against the channel shank and the awl point is pressed outwardly through the shielding layers of the cable. The cable body 24 is then drawn and twisted back and forth to enlarge the aperture 23 in cable wall and expose the inner wire the end of which is drawn from within the concave awl shank 12 in Figures 3 to 6, and outwardly through aperture 23 as indicated at 22 in Figure 8.

Another method of procedure used when it is desired to remove a very small portion of inner wire from the cable for the purpose of making a single external connection without severing either the inner wire or the cable, is shown in Figures 9 and 10. Following the same general manipulative methods previously described, the awl point 2 is inserted through the shielding layers of the cable at a point 25 intermediate of the ends of the cable and adjacent to the point 26 at which a small U-shaped loop of the inner wire, 27 in Figure 9, is removed and enlarged to the desired size. Then, before the awl member is withdrawn from within the cable, this U-loop is twisted to provide a closed loop as seen at 27 in Figure 10 in which the twisted section 28 prevents the accumulated shielding material 29 and 30 from closing in over the inner wire when the awl member is withdrawn from within the cable. Finally, the insulation is removed from at least a portion of the loop of wire, and the desired connection is made.

A still different method is employed when two connection lead wires are to be removed at definitely spaced points intermediate of the cable ends when the lead wires are to be of specified lengths for the purpose, for instance, of incorporating an external element into the electrical circuit of which the inner wire is a part. The

location of the point of removal of the first of the two lead wires is measured off and marked on the surface of the cable (see point K in Figure 11) and measuring in the proper direction therefrom the distance of the desired spacing between the lead wires, the point of removal of the second lead wire P in Figure 11, is similarly marked on the surface of the cable. The exact point between the removal points K and P at which the inner wire will be severed (point S in Figure 11) to provide the two lead wires required for connection to the external element, will depend upon the relative length of the two lead wires and upon the combined length of the two lead wires as compared with the length of the spacing between the removal points K and P. If the combined length of the two lead wires is less than the spacing between the removal points and the lead wires are to be of unequal length, the length of the first lead wire is measured inwardly of space K—P from the proper removal point to determine the point of severance, and the second lead wire 20 which will obviously be too long, is trimmed to proper length after removal from the cable; if the combined length of the two lead wires is less than the spacing between the removal points and the two lead wires are to be approximately the same length, the point of severance 25 is located midway between the point K and P and the lead wires are trimmed to the desired length after removal from the cable; if, however, the combined length of the two lead wires is greater than the spacing between the removal points, the amount of spacing is increased 30 accordingly, or the length of the first lead wire is measured inwardly from the established first point of removal, and the additional length required for the second lead wire drawn from within the cable shielding beyond point P.

Having established the location of the point of severance in either of the manners just described, the awl point 2 is inserted through cable shielding at removal point P in Figure 11 and run along the inner wire and out through cable side wall at point S, the inner wire 40 being exposed by means of manipulative methods previously explained. The inner wire is severed at point S, the awl member is withdrawn from within the cable shielding and re-inserted in the opposite direction through point S and is moved along the inner wire to emerge at point P 45 through which the adjacent end portion of inner wire is removed. This procedure is then repeated from point S in the opposite direction to point K where the other end portion of inner wire is removed and, finally, adjustment is made in the relative length of the two lead wires as 50 previously explained.

While in order to comply with the statute, the invention has been described in language more or less specific as to structural features, it is to be understood that the invention is not limited to the specific features shown, 55 but that the means and construction herein disclosed comprise a preferred form of putting the invention into effect, and the invention is therefore claimed in any of its forms or modifications within the legitimate and valid scope of the appended claims.

What is claimed is:

1. A device for use in withdrawing a portion of the inner wire from a shielded electric cable comprising: a shielding penetrating member having a flat rounded point at one end thereof, said member having parallel sides along a major portion of its length and extending 65 perpendicularly on each side thereof, said sides being sufficiently spaced apart to extend around a major portion of the periphery of said inner wire in said shielded cable as said member is manipulated therebetween after penetration of said shielding, said sides being gradually reduced in height adjacent to said penetrating end to define a tapered point thereon, a handle for said member, said handle having a central cavity adapted to receive and retain the opposite end of said member, a clamping lever 70 pivotally attached to said handle and adapted for move- 75

ment toward said shielding penetrating member to firmly clamp said cable shielding therebetween while said member is manipulated inside said shielding to prevent relative movement thereof while said inner wire is withdrawn from within said shielding, and an elastic element connected between said clamping lever and said handle tending to urge said clamping lever toward said handle.

2. A tool for use in withdrawing a portion of the inner wire from a shielded electric cable comprising: a shielding penetrating member shaped to penetrate and enter said shielding and partially extend around the periphery of said inner wire in said shielded cable as said penetrating member is moved therebetween after penetration of said shielding, a handle mounted on one end of said member, and shielding clamping means connected to said handle and operable to firmly clamp said cable shielding while said penetrating member is manipulated inside said shielding to prevent relative movement of said shielding while said inner wire is withdrawn therefrom.

3. A tool for withdrawing a portion of a wire from a shielded cable, comprising an elongated member of channel cross-section capable of penetrating the shielding of said cable, the sides of said channeled member being sufficiently spaced apart to recess at least a major portion of the inner wire around the periphery thereof as said member is moved along the extent of said cable between said shielding and said wire, a handle mounted

on the opposite end of said member, and a shielding clamp pivotally connected to said handle and movable against said shielding when said member is positioned therewithin to firmly contact a portion of said shielding and prevent relative movement thereof as said wire is withdrawn therefrom.

4. A tool for use in withdrawing a portion of a wire from a shielded cable, comprising an elongated member of channel cross-section capable of penetrating the exterior shielding of said cable, the sides of said channeled member being sufficiently spaced apart to recess at least a major portion of the inner wire around the periphery thereof as said member is moved along the extent of said cable between said shielding and said wire, a handle mounted on the opposite end of said member, and spring loaded clamping means connected to said handle and movable against the force of said spring to contact and clamp said shielding when said member is positioned therewithin to prevent relative movement of said shielding when said wire is withdrawn therefrom.
